UNITED STATES PATENT OFFICE.

GIUSEPPE CANNISTRA, OF NEW YORK, N. Y.

FLYING-MACHINE.

1,332,801.

Specification of Letters Patent. Patented Mar. 2, 1920.

Application filed May 13, 1919. Serial No. 296,789.

To all whom it may concern:

Be it known that I, GIUSEPPE CANNISTRA, a citizen of the United States, residing at Bronx, in the county of Bronx and State of New York, have invented new and useful Improvements in Flying-Machines, of which the following is a specification.

This invention relates to flying machines of the triplane type, and its object is to provide a machine of this character which possesses increased efficiency, combining therewith a novel form of under carriage, providing the under-carriage with a central boat arranged in vertical alignment with the body and further, the provision of side balancing floats, said boat and floats arranged with due regard to the plane surfaces and the machine thus balanced to effect proper stabilization.

Another object of the invention resides in the provision of a body construction having a maximum load carrying capacity, the said body being also designed and provided with fuel tanks arranged side by side so as to provide an intervening air channel therebetween for the purpose of reducing head resistance, while providing an arrangement of the tanks whereby large supplies of fuel can be carried.

A still further object of the invention resides in the novel construction of a flying machine body, the same including a frame having a buoyant boat-like base, a plurality of over-lying passenger accommodating cabins, an interposed deck between the cabins, and power plants supported by said deck, the deck section of the frame being formed with proper regard to the vertical center of the structure so as to give proper balance to the machine when in flight.

40 A still further object of the invention resides in the provision of a novel body and plane construction, and means for bracing and connecting the plane surfaces with respect to the body.

45 In the drawings:

Figure 1 is a front view of the body and the connected plane surfaces.

Fig. 2 is a side view thereof.

Fig. 3 is a plan view of the same.

50 Fig. 4 is a side view of the frame of said body.

Fig. 5 is a section taken on line 5-5 of Fig. 4.

55 In carrying the invention into practice, use is made of a body 10 consisting of a

frame of suitable material, the same including a hull section 11, at the base of the frame, an over-lying cabin section 12, a rectangular deck 13, fuel tanks 14-14, supported upon the deck respectively at the 60 opposite sides of the longitudinal center thereof, and a second cabin section 15, overlying said fuel tanks.

The hull section 11 preferably includes 65 transverse arched bars 16, a keel forming bar 17, side bars 18-18, the latter having connection with the arched bars 16, a central reinforcing bar 19, and vertical braces 20 between the keel bar 17 and said upper bar 19. It will of course be understood that the 70 hull section is to be provided with any suitable well known covering such as shown at 21.

The cabin section 12 consists of vertical 75 bars 22 which extend between the hull section and the deck 13, intermediate side bars 23, side bars 24-24 and arched braces or top bars 25, the branches of said arched bars having connection with the side bars and as illustrated the vertices of said branches are 80 connected with the said deck 13. The cabin is also provided with a suitable covering 26.

Between the boat section 11 and the sides of the deck 12 are angularly disposed brace bars 27. At each corner of the rectangular 85 deck 13 is a power plant 28, the same being mounted in a suitable housing 29. The fuel tanks 14-14 which rise from the deck are spaced apart to provide an intermediate air channel 30 therebetween so as to reduce head 90 resistance when the machine is in flight.

Cross bars 31 extend horizontally between the tanks 14-14 and supported from said cross bars is the mentioned upper cabin 15. At each end of said upper cabin is a power 95 plant 32. It will of course be understood that the deck 12 may be provided with suitable flooring as shown at 33.

The body construction previously referred to is used principally in connection with 100 heavier than air machines of the triplane type and as illustrated, the intermediate plane surface 34 has its inner ends secured to the body at a point preferably above the fuel tanks 14-14. The upper plane surface 105 35 is connected respectively with the body and with the surface 34 by struts 36-36 and struts 37. The lower plane surface 38 has its inner ends connected with the body at a point in line with the top of the hull section 110

11. This lower plane surface is connected with the intermediate surface 34 by means of struts 39.

5 Side pontoons 40—40 are secured to the lower plane surface 38 so as to give lateral balance to the machine when the latter is afloat in the water.

10 Between the intermediate plane surface and the deck of the body are braces 41 and 10 between said deck and the lower plane surface 38 are similar braces 42, the lower ends of which are disposed at points adjacent to the pontoons 40 so as to give ample strength and rigidity to said lower plane surface as 15 will be understood. Suitable guy wires 43 are connected between the hull like base of the body and the lower plane surface. Adjustable guy wires 44 are also arranged between the braces 41 and the upper cabin 20 section 15 of the machine.

The hull section of the machine is supported from an under-carriage 45 which includes a front wheeled axle 46 and a rear wheeled axle 47. The boat-like base of the 25 machine is provided with a rudder 48 which is so disposed as to be partly immersed in the water when the machine is afloat whereby the machine can be properly guided. The latter also serves to permit the machine 30 to be properly steered while in flight. A controlling mechanism 49 for the latter includes a suitable actuating shaft 50. The elevators 51 are mounted upon a shaft 52 having a pinion 53 thereon which meshes 35 with a driving worm 54, the latter receiving its power from an actuating shaft 55.

What is claimed as new is:—

1. A heavier than air machine comprising a body, including a frame, said frame being 40 substantially of rectangular form and provided at each of its corners with a power plant, plane surfaces carried by said frame, a vertically rising portion at the center of the frame, power plants supported by said 45 vertically rising portion, all of said power plants disposed between the plane surfaces, and an under carriage supporting said frame.

2. A heavier than air machine comprising 50 a body, including a frame, said frame being substantially of rectangular form and provided at each of its corners with a power plant, plane surfaces carried by said frame, a vertically rising portion at the center of 55 the frame, power plants supported by said vertically rising portion, all of said power plants disposed between the plane surfaces, and an under carriage supporting said frame, said frame including a boat structure 60 extending longitudinally between the wheels of the under carriage and side balancing floats supported from the lower plane surface.

3. A body for flying machines comprising 65 a lower boat structure having a central ver-

tically rising cabin, a substantially rectangular deck extending across the cabin, braces between the deck and said underlying boat structure, a power plant at each corner of the deck, fuel tanks supported upon the 70 deck respectively at opposite sides of the longitudinal center of the boat structure, a cabin over-lying the fuel tanks, and a power plant at each end of said second cabin.

4. A flying machine body, comprising a 75 cabin, a rectangular deck over-lying the cabin, a power plant at each corner of the deck, fuel tanks supported upon the deck respectively at opposite sides of the longitudinal center of the cabin, a cabin over- 80 lying the fuel tanks, and a power plant at each end of said second cabin.

5. A flying machine body comprising a frame having a longitudinally arranged cabin section and an over-lying deck, and 85 fuel tanks supported by the deck respectively at opposite sides of the longitudinal center of said cabin section so as to provide an intervening air channel between said tanks, and power plants supported by the 90 deck at the corners thereof.

6. A flying machine comprising a body having a centrally disposed boat structure, a deck over-lying the boat structure, a plurality of plane surfaces secured to the body, 95 braces between the boat structure, and the deck, the boat structure under-lying the lower plane surface, pontoons supported by said lower plane surface and braces between said lower plane surface and the deck, said 100 braces terminating at their lower ends at points adjacent to said pontoons.

7. A body construction consisting of a frame having a buoyant base and an over-lying rectangular deck, superposed plane 105 surfaces secured to the body, the buoyant portion of the body under-lying the lower plane surface, pontoons supported by the lower plane surface, braces between the deck and the lower plane surface, and braces between the deck and the next superposed plane surface.

8. A flying machine body and plane construction, consisting of a frame having a buoyant base, upper and lower plane surfaces 115 having connection with the body, a deck over-lying the buoyant base of the body, power plants supported by said deck, the buoyant base of the body under-lying the lower plane surface, pontoons supported 120 by the lower plane surface, braces between the lower plane surface and the deck, braces between the deck and the intermediate plane surface, struts between the lower plane surface and the intermediate plane surface, and 125 struts between the intermediate plane surface and the upper plane surface.

In testimony whereof I affix my signature.

GIUSEPPE CANNISTRA.
